FOREIGN PATENT DOCUMENTS

FR 2676762 A1 11/1992

Primary Examiner—Doris Clark*(74) Attorney, Agent, or Firm*—Edward Dreyfus(57) **CLAIM**

The ornamental design for a fuel dispenser guard assembly, as shown and described.

DESCRIPTION

FIG. 1 is a frontal-side perspective view of a fuel dispenser guard assembly showing my new design;

FIG. 2 is a front view thereof;

FIG. 3 is a top view thereof.

FIG. 4 is a rear view perspective thereof.

FIG. 5 is a second embodiment of the fuel dispenser guard assembly.

FIG. 6 is a front view of the fuel dispenser guard assembly of FIG. 5.

FIG. 7 is a top view of the fuel dispenser guard assembly of FIG. 5; and,

FIG. 8 is a rear view of the assembly of FIG. 5.

The broken lines in the figures are for illustrative purposes only and form no part of the claimed design.

The guard assembly is intended to rest on an automobile driving surface.
